UNITED STATES PATENT OFFICE.

WILLIAM COAN, OF VINCENNES, INDIANA.

SUMP-HOPPER.

1,202,163.

Specification of Letters Patent. Patented Oct. 24, 1916.

Application filed December 17, 1915. Serial No. 67,393.

To all whom it may concern:

Be it known that I, WILLIAM COAN, citizen of the United States, residing at Vincennes, in the county of Knox and State of Indiana, have invented certain new and useful Improvements in Sump-Hoppers, and do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to "sump hoppers" for coal mine shafts, and has for its object to provide an arrangement for salvaging the coal from the sump in a simple, cheap and effectual manner.

20 With this object in view, the invention consists in the novel construction of the sump hopper, in the novel construction and arrangement of the shifting rails and in the general arrangement and combination of the 25 parts, all of which will be first fully described and afterward specifically pointed out in the appended claims.

Referring to the accompanying drawings; Figure 1 is a vertical longitudinal sectional view through a pair of mine shafts illustrating a sump hopper in each and a mine car in position to receive coal from one of the sump hoppers. Fig. 2 is a vertical transverse sectional view through the same. Fig. 3 is a horizontal sectional view through the shafts looking down into the sums. Fig. 4 is a vertical transverse sectional view through one of the shafts and its sump illustrating the shifting rails out of their normal position. Fig. 5 is a vertical longitudinal sectional view through one of the shafts and its sump illustrating the shifting rails out of their normal position.

Like numerals of reference indicate the 45 same parts throughout the several figures in which:

1 and 2 indicate two mine shafts having the usual standards or frame pieces 3.

4 indicates the vertical guides between 50 which the elevators or cars 5, and the sump hoppers 6 slide, said elevators or cars 5 and sump hoppers 6 being provided with slides 7 and 8 as shown in Figs. 1 and 2.

9 and 10 indicates the sums of the shafts 55 which are really pockets at the bottom of the shafts below the mine car tracks and are

provided for the purpose of catching coal which is jolted and falls from the cars. Each of the sums 9 and 10 is provided with a sump hopper 6 which as shown on the 60 right of Fig. 1 is normally disposed within each sum so as to receive the coal falling from the shafts 1 and 2, said sump hoppers 6 being provided with suitable chains 11 for ready connection with the shaft elevators or 65 cars as also illustrated in Fig. 1.

The sump hopper 6 being of sufficient size to catch all of the coal falling through the shaft, it is essential that the mine car tracks be removed in order to allow the sump hopper to be raised in the shaft, and this is accomplished in the following manner: The stationary mine car rails 12 terminate at the shafts 1 and 2 as will be seen from the accompanying drawings. Hingedly mounted 70 at 13 at each side of the sums and at a point below the plane of the stationary rails 11 are shifting rails 14 and 15, which by reason of the crank shafts 16, operating levers 17 and links 18 can be shifted out of their 75 normal position shown in Fig. 2 into their retracted position shown in Fig. 4. When the shifting rails 14 and 15 are shifted into position shown in Figs. 1 and 2, they are brought into alignment with the stationary 80 rails 12. When however the shifting rail 14 is moved into this position, a space occurs 85 between the contiguous ends 19 and 20 of the rails 14 and 15 as shown in Fig. 5, said space or opening being caused by the vertical 90 guide 4, which as is shown in drawing extends within the shaft and sum. In order to close up this space or opening between the contiguous ends of the shifting rails when 95 the same are moved into alignment with the stationary rails 12, the shifting rail 14 is mounted on links 21 positioned and arranged as shown, so that said rail 14 is capable of being shifted longitudinally of the shaft as from position shown in Fig. 5 into position 100 shown at the left of Fig. 1. This longitudinal movement of the rail 14 causes its end 19 to meet the contiguous end 20 of the shifting rail 15 to close up the space or opening between the same.

105 It will be understood from Fig. 1 that each of the shafts 1 and 2 are provided with longitudinally shifting rails 14 which when shifted move toward each other. This longitudinal movement of the rails 14 creates a space or opening between the ends 110 of said rails 14 and the contiguous ends of

the stationary rails 12. In order to provide for this and form a continuous track as shown in Fig. 3, I dispose a short rail section 22 preferably pivoted at 23 which is 5 swung into alinement with the stationary and the shifting rails to provide a perfectly continuous track for the mine cars.

Having thus described the several parts of this invention, its operation is as follows:

- 10 The rails being normally in position shown in Figs. 1 and 2, and the sump hoppers 6 being within the sums 9 and 10, the mine cars are run on the rails into the shafts to be loaded on to the elevator on car 5. This 15 continuous operation causes a considerable quantity of the coal to fall into the sump hoppers 6. When said hoppers are full of coal and it becomes necessary to raise the same, the pivoted rail sections 22 are swung 20 out of alinement with the shifting and the stationary rails, and each of the longitudinally shifting rails 14 is shifted into position shown in Fig. 5 thus allowing them to clear the vertical guides 4 when the shifting rails 14 and 15 are shifted into position shown in Fig. 4 which is accomplished by throwing the operating levers 17 from position shown in Fig. 2 into position shown in dotted lines in Fig. 4. The shifting rails 30 being in retracted position shown in Fig. 4, are out of the way of the sump hopper 6, which is then connected to the elevator or cage 5 by means of the chains 11, and the sump hopper 6 is raised into position shown 35 on the left of Fig. 1. The shifting rails 14 and 15 and the pivoted rail sections 22 are then brought into their normal position by reversing the operation just described and a car is run onto the shifting rails into position shown on the left of Fig. 1. The coal 40 from the sump hopper 6 is then dumped into the car in a manner which will be now described.

Each sump hopper is provided with a 45 bottom 24 composed of two sections 25 and 26 hinged at 27, each section being provided with a pin 28 engaged by a latch 29 pivoted at 30, the upper end of each latch being engaged and held by a pivoted link 50 31; while pivoted to each bottom section 25 and 26 is a yoke 32 operating in connection with a pin 33 on the sump hopper. By raising the links 31, the latches 29 release the bottom sections 26 and 27, allowing them 55 to drop into position shown in dotted lines in Fig. 2 to dump the coal into the car directly thereunder, the yokes 32 acting as stops to limit the swing of the bottom sections in a manner which will be clearly understood. When the car has received the 60 coal from the sump hopper, it is run out of the shaft or into the next shaft to be loaded on the elevator or car 5, while the shifting tracks in the shaft under the dumped sump hopper are shifted into their retracted posi-

tion to allow the sump hopper to again enter the sump; after which the shifting tracks are again moved into their normal operative position to receive the mine cars for loading on to the elevator or cage, which 70 operation continues until the sump hopper again becomes filled with coal falling from the mine cars.

Having thus described the invention, it is evident that the same is susceptible to 75 changes and alterations in the construction and arrangement of the parts and I consider myself clearly entitled to all such changes and modifications as fall within the limit and scope of the appended claims.

I claim—

1. A device of the character described including a mine shaft elevator car operable in a mine shaft, a sump hopper within the sump of a mine shaft and means for connection between said sump hopper and said elevator car. 85

2. A device of the character described including a mine shaft elevator car operable in a mine shaft, a sump hopper within the sump of a mine shaft, means for connection between said sump hopper and said elevator car and removable rail sections in said mine shaft above the sump. 90

3. A device of the character described including a mine car operable in a mine shaft, a sump hopper operable in the sump of the mine shaft and capable of connection with the elevator car, said sump hopper including means for dumping its contents. 95

4. A device of the character described including a mine shaft elevator car operable in a mine shaft, a sump hopper operable in the sump of the mine shaft, and capable of connection with the elevator car, said sump 105 hopper including means for dumping its contents, and removable rail sections above the sump.

5. The combination with an elevator car operable in a mine shaft, and a mine car 110 entering the mine shaft of a sump hopper removably arranged in the sump of the mine shaft, and means of connection between said elevator car and said sump hopper.

6. The combination with an elevator car 115 operable in a mine shaft and a mine car entering the mine shaft of a sump hopper in the sump of the mine shaft and removable therefrom with said elevator car, and removable track sections for said mine car in 120 said mine shaft above the sump.

7. The combination with an elevator car operable in a mine shaft and a mine car entering the mine shaft of a sump hopper in the sump of the mine shaft and removable 125 therefrom with the elevator car, said sump hopper including means for dumping its contents into said mine car.

8. The combination with an elevator car operable in a mine shaft and a mine car 130

entering the mine shaft of a sump hopper in the sump of the mine shaft and removable therefrom with the elevator car, said sump hopper including means for dumping its contents into said mine car and removable rail sections for said mine car in said mine shaft above the sump.

9. A sump hopper for mine shafts including means for connection with a mine shaft elevator car and including means for dumping its contents into a mine car in combination with removable track sections for the mine car disposed normally above the sump hopper.

10. The combination with a sump hopper in a mine shaft and a mine car for receiving the contents of the sump hopper of laterally movable track sections for the mine car above the sump hopper.

11. The combination with a sump hopper

in a mine shaft and a mine car for receiving the contents of the sump hopper of longitudinally movable track sections for the mine car above the sump hopper.

12. The combination with a sump hopper 25 in a mine shaft and a mine car for receiving the contents of the sump hopper of laterally and longitudinally movable track sections for the mine car above the sump hopper.

13. The combination with a sump hopper 30 in a mine shaft and a mine car for receiving the contents of the sump hopper of hinged track sections for the mine car above the sump hopper.

In testimony whereof, I affix my signature, in presence of two witnesses.

WILLIAM COAN.
